United States Patent

Des. 238,374

Patented Jan. 6, 1976

238,374

WALL MOUNTED TELEPHONE

John E. Davis, Sun Valley, and Wayne E. Bulgrin, Lone
Pine, Calif., assignors to Lockheed Aircraft Corpora-
tion, Burbank, Calif.

Filed Oct. 1, 1973, Ser. No. 402,617

Term of patent 14 years

Int. Cl. D14—03
U.S. Cl. D26—14 G

Fig. 1

FIG. 2

FIG. 3

FIG. 4

FIG. 5

FIG. 6

FIG. 1 is a perspective view of a wall mounted telephone showing our new design;

FIG. 2 is a top plan view thereof;

FIG. 3 is a left side elevation thereof;

FIG. 4 is a front elevation thereof;

FIG. 5 is a right side thereof;

FIG. 6 is a bottom plan view thereof;

FIG. 7 is a front perspective view of a telephone with the handset mounted in the cradle;

FIG. 8 is a side elevation with portions shown in section; and

FIG. 9 is a fragmentary side elevation with the handset in an alternate position and portion shown in section.

We claim:

The ornamental design for a wall mounted telephone, as shown and described.
